UNITED STATES PATENT OFFICE.

WALTER LENCHARD, OF MCKEESPORT, PENNSYLVANIA.

TOY SHOOTING-GALLERY.

1,355,765.

Specification of Letters Patent. Patented Oct. 12, 1920.

Application filed August 15, 1919. Serial No. 317,797.

To all whom it may concern:

Be it known that I, WALTER LENCHARD, a citizen of the United States, residing at McKeesport, in the county of Allegheny and State of Pennsylvania, have invented new and useful Improvements in Toy Shooting-Galleries, of which the following is a specification.

This invention relates to toys, and more particularly to a shooting gallery.

One of the main objects of the invention is to provide a toy of simple construction and operation which is well adapted to instruct children in the aiming and firing of a gun. A further object is to provide a toy which shall be both interesting and amusing in which, when the player makes the "bull's eye," a figure will be displayed to signify this fact. A further object is to provide simple and efficient means for aiming the gun. Another object is to provide means for causing movement of the figure when the "bull's eye" is made and for setting the figure or returning it to its initial position. Further objects will appear from the detailed description.

In the drawings:

Figure 1 is a side view, partly broken away, of a shooting gallery constructed in accordance with my invention.

Fig. 2 is a section taken substantially on line 2-2 of Fig. 1.

Fig. 3 is an end view of the gallery.

Fig. 4 is a section taken substantially on line 4-4 of Fig. 3.

Fig. 5 is a similar view taken on line 5-5 of Fig. 3.

Fig. 6 is a fragmentary detail of the movable figure.

Fig. 7 is a top plan view of the gun.

Fig. 8 is a section taken substantially on line 8-8 of Fig. 7.

Fig. 9 is a fragmentary section through the lower portion of the gun supporting base.

Fig. 10 is a vertical section through the gun supporting base taken in a plane at right angles to Fig. 9.

Fig. 11 is a section taken substantially on line 11-11 of Fig. 10.

Fig. 12 is a detail of the gun setting and releasing means.

The gallery consists of a supporting board 1, a vertically disposed target board 2 detachably secured to the supporting board at one end thereof, and a sheet metal retaining

wall or flange 3 secured to the supporting board and fitting snugly against the inner face of the target board, this retaining wall being so shaped as to effectually prevent a projectile from rebounding from the board out of the gallery. The target board 2 is provided at the central portion of its inner face with a plurality of concentric rings forming a target 4. These rings are concentric with a bull's eye 5 which is formed from a disk 6 secured upon the inner end of a cylindrical member 7 fitting snugly in an opening through target board 2. This member 7 is provided with a central outwardly projecting stem 8 which extends through a sheet metal casing 9 secured on the outer face of board 2. The outer end of stem 8 bears against the inner face of vertical arm 10^a of a substantially rectangular or L-shaped latch 10 mounted upon the casing 9. Member 7 is normally forced inwardly by an expansion coil spring 11 mounted about stem 8 and confined between the back wall 9^a of casing 9, inward movement of this member being positively limited by a pin 12 inserted through the stem and engaging the back wall of the casing.

As will be noted more clearly from Figs. 3 and 5, the horizontal arm 10^b of latch member 10 is disposed closely adjacent the top wall 9^a of casing 9. This arm is adapted to engage into a slot 13 extending transversely of the outer face of a rod 14 of rectangular cross section slidable through the upper and lower walls 9^b and 9^c, respectively, of casing 9. Rod 14 is forced upwardly by an expansion coil spring 15 mounted about the same and confined between the bottom wall 9^c of the casing and a pin 16 secured through the rod. A leaf spring 17 is secured to the back of casing 9 and presses against the upper arm 10^b of latch member 10 so as to normally hold the same in position for engagement into slot 13. As will be readily understood, when the bull's eye is struck so as to be forced rearwardly through target board 2, latch member 10 is forced outwardly against the pressure of spring 17 thus releasing rod 14 and permitting the same to be raised by spring 15.

A suitable figure 18 is secured upon the upper end of rod 14. This figure is stamped from sheet metal to provide a body 19 and head 20. Arms 21 are pivoted to the body 19 a short distance below their upper ends,

legs 22 being similarly connected to the body. Each of the arms 21 is provided with a link 23 loosely secured through the arm above the pivot 24 thereof, the links 23 being connected by a central link 25. Link 25 is loosely secured to the upper end of an operating rod 26 which is slidable through the upper of two spaced substantially L shaped brackets 27 secured upon the back wall of casing 9. The legs 22 are similarly connected to each other and to the operating rod. The lower end portion of rod 26 is turned outwardly at right angles to provide a stop finger 28 which is adapted for engagement with the brackets 27. These brackets are so spaced that when the figure is in lowered position, finger 28 will strike the lower bracket thus forcing the rod upwardly and insuring lowering of the arms and legs of the figure; and when the figure is released and rod 14 is raised, the finger 28 will engage the upper bracket 27 so as to limit upward movement of the rod 26 and insure that the arms and legs of the figure will be moved outwardly from each side thereof into substantial horizontal position, this movement occurring when the figure reaches the limit of its upward movement. In this manner, I insure that, when the "bull's eye" is made, the figure will be released and raised so as to be displayed above the target board, and movement of the limbs of this figure will be caused.

To move the rod 14 downwardly for lowering the figure 18, special means is provided. A sleeve 30 is freely slidable on the rod and is provided with laterally projecting ears 31 through which are secured the lower ends of two tension springs 32 secured 40 at their upper ends to the casing 9. These springs act to normally hold the sleeve in raised position. A setting wire 33 is connected at one end to the ears. This wire is passed over a suitable guide pulley 34 depending from board 1, and has its other end secured to a setting member 35 slidable through a cross bar 36 secured to the board 1 at the forward end thereof, this member being provided with a gripping element or 50 knob 37 to facilitate outward movement thereof, this knob also serving to positively limit inward movement of the member. The slot 30 is of such length that, when the rod 14 is in raised position, the spring is forced 55 at the lower end of this slot. By pulling the member 35 outwardly the rod 14 may be moved into lowered position, the springs 32 serving to raise the sleeve 31 and return member 35 to its original position upon release of this member.

At the opposite end of the base board from the target there is mounted a gun 38. This gun is formed of sheet metal and includes a barrel 39 to each side of which is secured a cylindrical casing 40. The for-

ward end of this casing is closed by a plug 41 secured therein, from the inner face of which extends a U-shaped member or stirrup 42. A band 43 of rubber or other suitable elastic material is passed through member 42, at its forward end, and about a finger 44 projecting horizontally from a plunger 45 operable in the barrel, the barrel and the casings 40 being provided with aligned slots to accommodate the fingers, forward travel 75 of the plunger being positively limited by contact of the fingers with the casings at the forward ends of the slots.

A setting rod 47 is secured to the plunger centrally thereof and is slidable through the 80 back of the gun. This rod is provided, at its outer end, with a knob or button 48 secured thereon to facilitate drawing the plunger toward the back of the barrel, and the rod is of such length that this button is spaced 85 away from the back of the gun when the plunger is in its forward position thus preventing injury to the operator by getting his fingers caught between the button and the gun when the gun is fired. 90

The rod 47 is provided, a short distance from its inner end, with a transverse groove in its under face which is adapted to receive the upper edge portion of a setting and releasing lever 49 pivotally secured at one end, as at 50, to the back of the gun. This lever is normally held in raised position by a wire spring 51, the lower end of which is secured to the gun base, the upper end of this spring being loosely secured through 100 the lever. For convenience in operation the lever is provided with an extension or handle element projecting laterally of the gun by means of which the lever may be readily depressed for releasing the setting rod and thus firing the gun. 105

The gun is secured upon the base indicated generally by 53, this base consisting of an upper member or block 54 and a lower block 55, the upper block being provided with an extension 52 to which the gun is secured. A pivot bolt 56 is secured centrally through the two blocks and serves to connect the same so as to permit rotation of the upper block 54 upon the lower block. This upper block 115 is provided, to one side of the bolt 56, with a radially disposed groove 57 which slidably receives a cylindrical head 58 formed at the upper end of a stem 59 of a plate 60 which depends from the block into a recess 61 in the upper end of lower block 55. This plate 60 is centrally bored and threaded to receive the screw threaded rod or shaft 62 which is rotatably mounted through block 55 adjacent the upper end thereof, this shaft 120 being secured against longitudinal movement by inner and outer collars 63 and 64, respectively. A hand wheel 65 is secured upon the outer end of the shaft for facilitating rotation of the same. The reduced neck 125 130

or stem 59 of plate 60 is slidable in a slot 66 through a retaining plate 67 secured to the under face of block 54. By rotating shaft 62, the upper block 54 may be turned 5 in either direction about the pivot bolt 56 thus permitting lateral adjustment of the gun to be readily and easily effected.

The lower block is further provided in its lower portion, with a downward opening 10 recess 68. This recess receives the lower threaded portion of an adjusting shaft 69, which is rotatably supported in the block and is secured against axial movement by inner and outer collars 70. The screw 15 threaded portion of shaft 69 is threaded through an adjusting block 71 provided with lateral gudgeons 72 which operate in vertical slots 73 formed in the arms of a U bracket 74 which is pivotally secured to the 20 supporting board 1 for rocking movement about a vertical axis. By rotating the shaft 69, the lower block 55, which is pivotally supported between brackets 75 secured to board 1 so as to be rockable about a horizontal 25 axis, may be readily tilted so as to vary the inclination of the gun. By means of the turning and tilting devices above described, the gun may be readily aimed, and an appreciable amount of skill will be required in aiming the gun to hit the target or 30 the bull's eye.

The projection of the figure which is disclosed when the bull's eye is made is specially adapted to appeal to children, and the 35 adjustability of the gun has the additional advantage that it instructs the child in aiming and increases accuracy in judging distances and angles.

It may be found advisable in practice to 40 make slight changes in the construction and arrangement of the details of my invention without departing from the field and scope of the same, and I intend to include all such variations, as fall within the scope of the 45 appended claims, in this application in which a preferred form only of my invention is disclosed.

What I claim is:

1. In a game apparatus, a target board, a 50 figure having movable limbs and arranged to be displayed above the board when raised, means for raising said figure, means for normally holding the figure lowered, means for extending the limbs of said figure when raised, a movable target carried by said board, and means actuated by the target when struck for releasing said means for holding the figure in lowered position.

2. In a game apparatus, a figure having 60 movable limbs normally in retracted position, a movable target, means for raising said figure, means for normally holding said figure lowered, means actuated by the target for releasing the figure upon the target being struck, a member connected to the

limbs of said figure so as to extend the same when the figure is raised and upward movement of the member is stopped, and means for positively limiting upward movement of said member. 70

3. In a game apparatus, a movable target, a figure having movable limbs, means for raising said figure, means for normally holding said figure lowered, means actuated by the target for releasing the figure upon the target being struck, and means for holding the limbs of the figure in retracted position when the figure is lowered and for extending said limbs when the figure is 75 raised. 80

4. In a game apparatus, a movable target, a figure having limbs pivoted thereto, means for raising said figure, a limb extending member loosely connected to said limbs above the pivots thereof, means for limiting upward movement of said member so as to extend the limbs of the figure when said figure is raised, means for normally holding the figure lowered, and means actuated by the target for releasing the figure upon the 85 target being struck. 90

5. In a game apparatus, a movable target, a figure having pivoted limbs, an operating rod loosely connected to said limbs above the pivots thereof, means for positively 95 limiting movement of said rod in either direction so as to cause raising and lowering of the limbs in accordance with movement of the figure, means for normally holding the figure lowered, means actuated by the 100 target for releasing the figure upon the target being struck, and means for raising said figure.

6. In a game apparatus, a movable target, a figure having pivoted limbs, an operating 105 rod loosely connected to said limbs above the pivots thereof, upper and lower stops, the rod being slid able through the upper stop and provided at its lower end with an element adapted to contact with either of 110 said stops for limiting movement of the rod in either direction, means for normally holding the figure lowered, means actuated by said target for releasing said figure upon the target being struck, and means for raising 115 the figure. 120

7. In a game apparatus, a vertically movable rod, a movable target, means for raising said rod, means for holding the rod lowered, means actuated by the target for releasing 120 the rod upon the target being struck, a figure comprising a body secured upon said rod and limbs pivoted to said body, a member connected to said limbs above the pivot points thereof, and means for limiting upward movement of said member so as to cause extending of the limbs of the body when said body is raised. 125

8. In a game apparatus, a supporting board, a gun base mounted thereon and com- 130

posed of a lower member supported for movement about a horizontal axis and an upper member mounted on said lower member for adjustment about a vertical axis,
5 a gun carried by said upper member; an adjusting shaft carried by the lower member, connections between said shaft and the upper member and positioned within said base for turning the upper member
10 upon rotation of the shaft, a second adjusting shaft carried by the lower member, and connections between said second shaft and the supporting board and positioned within

the base for rocking said lower member about its axis upon rotation of the second 15 shaft.

9. In a game apparatus, a gun base composed of a lower member rockable about a horizontal axis and an upper member supported thereby and adjustable about a vertical axis, a gun carried by the upper member, means for adjusting said upper member, an independent means for adjusting the lower member. 20

In testimony whereof I affix my signature. 25
WALTER LENCHARD.
